CLAIM

The ornamental design for a combined solar energy charging device and lamp assembly, as shown and described.

DESCRIPTION

FIG. 1 is a front, left, top perspective view of a combined solar energy charging device and lamp assembly showing our new design;

FIG. 2 is a back, right, bottom perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof; and,

FIG. 9 is a partially enlarged view of FIG. 1.

The broken lines shown represent the boundary of the enlarged portion shown in FIGS. 1 and 9 and form no part of the claimed design.
